UNITED STATES PATENT OFFICE.

CHARLES W. HODGSON, OF PARK CITY, UTAH.

BELT-BUCKLE ATTACHMENT.

1,084,209.

Specification of Letters Patent.

Patented Jan. 13, 1914.

Application filed June 10, 1913. Serial No. 772,803.

To all whom it may concern:

Be it known that I, CHARLES W. HODGSON, a citizen of the United States, residing at Park City, in the county of Summit and 5 State of Utah, have invented certain new and useful Improvements in Belt-Buckle Attachments, of which the following is a specification.

My invention relates to improvements in 10 belt buckle attachments, and the leading object is the provision of an attachment which will not interfere with the natural and usual purpose of the buckle but which will operate in connection with the button or catch upon 15 trousers to retain the belt in proper position with reference to said trousers.

Another object of my invention is the provision of a device which can be easily applied and which cannot possibly work loose 20 or become detached and which will hold the belt and buckle in proper position and insure an attractive and ornamental appearance of the belt upon the trousers.

Another object of my invention is the 25 provision of a belt buckle attachment which can be applied with ease to buckles in use or at the time of manufacture by any person and which while not adding any material cost to the buckle will greatly increase 30 the efficiency, desirability and usefulness of the belt.

With these objects in view my invention consists broadly in the combination with the belt buckle of an attachment adapted to engage 35 and retain itself in position upon the buckle and having means to engage either the button or clasp of the trousers.

The invention further consists of a belt buckle attachment made from a single piece 40 of spring or elastic material having portions to engage the belt and the trouser button or the trouser clasp, all embodying novel features of construction and combination of parts substantially as shown, described, and 45 particularly defined by the claims.

Figure 1 represents a front or face view 50 of the buckle and part of the belt with my attachment in position with reference to the buckle and belt. Fig. 2 is a horizontal sectional view of a portion of the belt, buckle and trousers showing my attachment applied and employed in connection with trousers using the usual clasp and keeper fastening. Fig. 3 is a similar view the device being 55 used in connection with the usual button

employed in fastening the trousers, and Fig. 4 is a perspective view of my attachment removed and shown on an enlarged scale for purpose of clearer illustration of the device.

My device is of extremely simple construction consisting of a single piece of material and is used in connection with the loop buckle A, having the usual fastening pin or tongue B, and the belt C, having one end D, looped around the buckle and the 65 other end which passes through the loop formed with openings E, to receive the tongue of the buckle.

My device is formed with the pair of lateral arms F, which fit between the looped 70 end of the belt and buckle and secure the device in place.

The device is formed with the pair of inclined arms G, one of which is formed with an inwardly extending eye or loop H, which 75 engages the button J, when used upon a pair of trousers employing such a fastening and is further formed with the inturned or off-set cross-bar H' which forms an engaging loop which fits within the clasp K, and 80 keeper L, such as used upon trousers employing this character of fastening.

The operation of my device will be readily understood from the description and drawing and it will be noted that the device 85 can be used with either a button fastening or with a clasp and keeper fastening adapting the device for trousers using either character of fastening means, thus making the device highly desirable. It will also be apparent 90 that the device can be easily applied and will under all conditions remain in proper position; will retain the belt in the exact relation to the trousers; will not add anything practically to the cost of the 95 buckle, and generally from every point of view will prove useful, practical, and efficient.

I claim:

1. A belt attachment, consisting of a single piece of material having a pair of oppositely extending lateral arms adapted to engage between the belt and buckle frame, a pair of inclined arms diverging from said lateral arms, a cross-bar connecting said inclined arms at their outer ends, and a button-engaging loop formed on one of said inclined arms and projecting into the space defined by said inclined arms and cross-bar. 100

2. A belt attachment, consisting of a single 105

gle piece of material having a pair of oppositely extending lateral arms adapted to engage between the belt and buckle frame, a pair of inclined arms diverging from said lateral arms, an inwardly offset cross-bar connecting said inclined arms at their outer ends, and a button-engaging loop formed on one of said inclined arms and projecting

into the space defined by said inclined arms and cross-bar.

10

In testimony whereof I affix my signature in presence of two witnesses.

CHARLES W. HODGSON.

Witnesses:

J. A. MURPHY,
L. R. PACKER.
